(57) **CLAIM**

The ornamental design for a suspended monitor system, as shown and described.

DESCRIPTION

FIG. 1 is a front view of the suspended monitor system according to one embodiment of the present invention;

FIG. 2 is a side view thereof;

FIG. 3 is another side view thereof;

FIG. 4 is a rear view thereof;

FIG. 5 is a bottom view thereof;

FIG. 6 is a top view thereof;

FIG. 7 is a perspective view thereof;

FIG. 8 is a front view of the suspended monitor system according to a second embodiment of the present invention;

FIG. 9 is a side view thereof;

FIG. 10 is another side view thereof;

FIG. 11 is a rear view thereof;

FIG. 12 is a bottom view thereof;

FIG. 13 is a top view thereof;

FIG. 14 is a perspective view thereof;

FIG. 15 is a front view of the suspended monitor system according to a third embodiment of the present invention;

FIG. 16 is a side view thereof;

FIG. 17 is another side view thereof;

FIG. 18 is a rear view thereof;

FIG. 19 is a bottom view thereof;

FIG. 20 is a top view thereof; and,

FIG. 21 is a perspective view thereof.

The broken line showing of portions of the suspended monitor system forms no part of the claimed design.
